United States Patent Office

Des. 194,498
Patented Feb. 5, 1963

194,498

CHAIR

Zaner E. Miller, E. 814 Hoffman, Spokane, Wash.

Filed Mar. 24, 1961, Ser. No. 64,475

Term of patent 14 years

(Cl. D15—11)

FIG. 2.

FIG. 3.

FIG. 4.

FIGURE 1 is a perspective view of a chair embodying my design;

FIGURE 2 is a side elevational view of the chair;

FIGURE 3 is a front view of the chair; and

FIGURE 4 is a rear view of the chair.

The side opposite to that shown in FIG. 2 is plain and unornamental.

I claim:

The ornamental design for a chair, as shown and described.
